Attorney

UNITED STATES PATENT OFFICE.

JOHANNES EHRHORN HJORT, OF COPENHAGEN, DENMARK.

MORTISE LOCK.

Application filed August 17, 1921. Serial No. 492,965.

To all whom it may concern:

Be it known that I, JOHANNES EHRHORN HJORT, subject of King of Denmark, residing at Copenhagen, Denmark, have invented certain new and useful Improvements in Mortise Locks, of which the following is a specification.

The invention relates to a mortise bolt lock with tumblers and a very compact lock 10 casing adapted to be inserted in a small round hole bored into the door to be locked, instead of as heretofore into a long mortised hole.

The invention differs from the known lock 15 of this kind by its special shape of lock casing, so that the corresponding hole in the door, into which the lock is inserted, weakens the door as little as possible. Furthermore, the lock constructed according to the invention 20 is characterized by the bolt-tail being disposed in the central plane of the lock, so that the key-bit will only need one projection in order to move the bolt, even if the key has to be inserted from either side of the lock. Finally, according to the invention, 25 all the tumblers are pivoted at one end about a pin at the end farthest from the face plate, and are engaged by the key-bit about half way between the said pivot and the tumbler-head. This feature necessitates the individual steps in the key bit corresponding to the individual tumblers to be shaped very accurately with the proper projection, as any error will be nearly doubled at the tumbler-head, and the lock will thereby become 30 more difficult to pick.

On the drawing, which illustrates one construction of the invention,

Fig. 1 shows the lock in side elevation, 40 with the cover removed,

Fig. 2 the same in top view, and

Fig. 3 the same viewed from the rear end.

1 is the so-called face plate which by means of screws or the like fastens the lock 45 in position, 2 is the lock-casing shaped as a cylinder with two flat segmental faces parallel to the bolt 3. The bolt 3 is centrally disposed in the lock-casing and is fitted with an inwardly directed extension 4 located in the same plane as the bolt and fitted with two guiding lugs 5 and 5', which are guided in corresponding recesses 6 and 6' provided in the two cylindrical walls of the lock-casing 2, midway between its two plane walls. 50 7 is the key hole and 8 a recess in the bolt

corresponding to the key, the said recess being engaged by the central projection of the key-bit, which thus moves the bolt, when the key is being turned. 9 is one of the tumblers which are pivoted, at their inner 60 ends about a pin 10 and each of which supports, at its outer end, a flat spring 14 resting against a stud 15. Hereby the specially shaped heads 11 of the tumblers are pushed, in known manner, beyond one of two lugs 65 12 and 12' provided on the bolt 3, 4, in such a manner that the bolt cannot be moved until all the tumblers have been lifted, by the key-bit against the action of the individual springs 14, exactly so far that the 70 heads 11 of the tumblers will allow the two lugs 12 and 12' of the bolt to pass.

The lock casing is most conveniently formed by two symmetrical parts, which are joined by riveting of the studs 10 and 15, or 75 by means of screws 16 passing through the same.

Having now particularly described and ascertained the nature of my said invention and in what manner the same is to be performed, I declare that what I claim is:—

1. A mortise lock, comprising a substantially-cylindrical lock casing, a key-actuated bolt slidable therein and provided at one side with spaced upper and lower laterally-projecting lugs, and a tumbler pivoted in the casing on the same side of the bolt as the lugs and extending at its free end into the space between the lugs; said tumbler having a head adjacent its free end for cooperation 80 with said lugs and normally engaged with one of them to prevent retraction of the bolt, but adapted to be moved out of such engagement by the action of the key to permit the bolt to be retracted, said head having a 85 height such as to enable it to pass through the space between the lugs during the movements of the bolt.

2. A mortise lock, comprising a substantially-cylindrical lock casing, a key-actuated 100 bolt slidable therein and provided at one side with centrally-located, spaced upper and lower laterally-projecting lugs, and provided in advance of said lugs with a longitudinal guide slot, a stud mounted in the 105 casing and extending horizontally through said slot, a tumbler pivoted at its rear end in the casing on the same side of the bolt as said lugs and having its free front end extending into the space between the lugs, and 110

a spring attached to the front end of the tumbler and engaging said stud; said tumbler having adjacent its free end a head which is normally engaged with the lower lug by the pressure of the spring to prevent retraction of the bolt, but adapted to be moved out of such engagement by the action of the key to permit the bolt to be re-

tracted, said head having a height such as to enable it to pass through the space between the lugs during the movements of the bolt.

In testimony whereof I have affixed my signature,

JOHANNES EHRHORN HJORT.
